UNITED STATES PATENT OFFICE.

GEORGE GOODING AND BENJAMIN W. GOODING, OF PLYMOUTH, MASSACHUSETTS.

DESIGN FOR A HANDLE FOR SPOONS, &c.

SPECIFICATION forming part of Design No. 20,664, dated April 7, 1891.

Application filed January 17, 1891. Serial No. 378,162. Term of patent 14 years.

To all whom it may concern:

Be it known that we, GEORGE GOODING and BENJAMIN W. GOODING, citizens of the United States, residing at Plymouth, in the county of 5 Plymouth and State of Massachusetts, have invented and produced a new and original Design for the Handles of Spoons and other Articles, of which the following is a specification, reference being had to the accompanying drawing, forming a part thereof, in which the figure represents a face view of a spoon-handle having my design produced on its handle.

The leading feature of my design consists 15 in the representation of a rock on the handle, the marginal defining-lines of which merge into the surface of the handle.

In the drawing, *a* is the rock which appears to rise from the handle, and its marginal defining-lines merge into the surface of 20 the handle.

I claim—

The herein-described design for the surface ornamentation of the handles of spoons, forks, and other articles, consisting in the representation of a rock thereon, the marginal defining-lines of which merge into the surface of 25 the handle, as shown and described.

GEORGE GOODING.
BENJAMIN W. GOODING.
